UNITED STATES PATENT OFFICE.

BAYARD GUTHRIE, OF PITTSBURG, PENNSYLVANIA, AND JOSEPH P. KARCH, OF PLAINVILLE, CONNECTICUT.

ELECTRIC FURNACE.

979,663.

Specification of Letters Patent. Patented Dec. 27, 1910.

Application filed March 8, 1909. Serial No. 481,895.

To all whom it may concern:

Be it known that we, BAYARD GUTHRIE and JOSEPH P. KARCH, citizens of the United States, residing at Pittsburg, Allegheny county, Pennsylvania, and Plainville, in the county of Hartford and State of Connecticut, have invented certain new and useful Improvements in Electric Furnaces, of which the following is a specification.

10 This invention relates particularly to the melting of metals by the heat of the electric arc.

The main object is to provide a simple and reliable construction which is efficient and durable.

It is also desired to facilitate pouring and to produce a clean solid ingot without loss of metal.

The complete invention in its preferred form comprises a crucible and four radially movable electrodes in a tiltable casing which carries a swinging mold. The melting may be carried on in a neutral or reducing atmosphere.

25 The details will be more clearly understood from the following specification and the accompanying three sheets of drawings.

Figure 1 is a front view of one form of furnace. Fig. 2 is a plan view of the same with the top removed and showing a circuit diagram. Fig. 3 is an enlarged fragmentary plan view of one electrode and its operating mechanism. Fig. 4 is a side view and vertical section of the same. Fig. 5 is 35 an end view and partial section of the same. Fig. 6 is a vertical section of the furnace showing the crucible and the casing tilted for pouring. Fig. 7 is an enlarged vertical section of the casing and crucible showing 40 one of the trunnions.

45 Current.—The crucible 1, for containing the metal, the flux and other materials of a charge is located between the electrodes 2, 3, 4 and 5 which are arranged in pairs and supplied with current from the generator 6. This is of the quarter phase alternating current type. Two direct current machines might be used however if desired.

50 Casing.—The shell 7 of the casing is riveted or otherwise secured to the bottom plate 8 and reinforced by the hoop 9. Two brackets such as 10 are riveted or otherwise secured to the bottom and side of the casing and each carries a trunnion 11. The two trunnions 11, 11 are journaled in the stand-

ards 12, 12. A gear wheel 13 on one of the trunnions meshes with pinion 14 and the hand wheel 15 is provided for rotating pinion 14 and thus tilting the casing and crucible for pouring. The interior wall and the bottom of the casing is lined with a plastic composition 16 such as clay and asbestos fiber. A fire brick floor and piers such as 17 are provided to support the crucible between the electrodes. A perforated fire clay stand 18 is provided when a neutral or reducing atmosphere is desired, the gas being admitted through the pipe 19.

Crucible.—The crucible is made of a suitable composition such as plumbago, clay and sand in proper proportions and sufficiently free of oxid of iron so as to prevent the formation of carbide of silicon in the operation of the furnace so far as possible. The lower or melting part of the crucible is of the usual shape such for instance as is used in melting steel. The mouth is preferably funnel shaped as at 20 to increase its capacity and for convenience in filling. The cap 21 fits into this mouth 80 portion and when new sits at the top and gradually sinks lower as it wears away in use. The cover 22 of the casing is held down by stay bolts such as 23, 23. A discharge spout or pipe 24, for instance of plumbago, 85 fits over the outlet lip 25 in the side of the crucible near the top and extends out through the wall of the casing.

Mold.—From a pair of hooks 26 secured to the top 22 is suspended the ingot mold 27 90 by means of the eye bolts 28, 28. The mold rests on the cross plate 29 and is wedged into the clamps 30, 30. A plumbago funnel 31 or phosphorizer is provided at the upper end of the mold. The axis on which the 95 mold swings is just in front of the discharge end of the crucible spout 24 so that as the crucible is tilted up the stream of metal pouring from the spout always falls straight down into the mold without splashing 100 against the cold sides or spilling. This uniform flow insures a perfectly sound ingot.

Electrodes.—Each of the four electrodes is radially movable to and from the crucible (see Figs. 3, 4 and 5). The face of the 105 electrode is shaped to correspond with the external contour of the crucible, the arc of its horizontal section being about 75° (see Fig. 3). The rear end is dove tailed and fits vertically into the spring jaws of the 110

holder 32 whose shaft 33 extends through the stuffing box or gland 34 and is secured in the clamp 35. The latter is mounted on a carriage 36 which slides on the guide bracket 37. A rotatable screw 38 carried by this bracket is engaged by the interiorly threaded half nut 39, which is secured to or formed as a part of the carriage 36. By rotating the screw 38, for instance by a handle 40, the nut 39 travels along the screw and moves the carriage 36, clamp 35 and the holder 32 and its electrode in or out as desired. In order to move all the electrodes simultaneously a bevel pinion 41 is mounted on the end of each screw 38 and all of them mesh with the bevel gear wheel 42. This is supported by a grooved wheel or shive 43 adjacent each pinion. Rotation of any one of the four screws and its pinion rotates the big gear and all the other pinions and screws so that all the electrodes are moved at the same time. Current is led to each electrode for instance by conductors such as 44. The holder is of course insulated properly from the carriage 36 and from the casing at the stuffing box 34. The electrodes and holders are coppered where they are in electrical engagement. The glands 34 should of course be properly packed to prevent leakage.

30 Operation.—The casing being horizontal as shown in Fig. 1, the crucible 1, is charged and the car placed on top and the electrodes 2, 3, 4 and 5 are all moved up into contact with the crucible. Current is then turned on and the crucible and its contents are in the circuits. This warms up the crucible and contents but as the electrodes are purposely made large and as the crucible and contents are relatively good conductors the heat is not great. The handle 40 is then applied to the end of one of the screws 38 and the electrodes are slowly withdrawn from contact with the crucible. Arcs immediately form between the pair of electrodes 2 and 3 and the pair 4 and 5 with the crucible in the center of intense heat. The great heat soon melts the contents of the crucible. The electrodes are then closed into contact with the crucible, the arcs gradually decrease and the current is turned off. The mold 27 being hung on the hooks 26, 26, the hand wheel 15 is rotated so as to tilt the furnace as shown in Fig. 6 and pour the contents of the crucible into the mold. The electrodes hold the crucible while pouring. When one mold is filled it can be quickly removed and another substituted and pouring continued until the crucible is empty. The furnace is then returned to its horizontal position of Fig. 1 and recharged and the operation repeated.

When it is particularly desired to avoid oxidation of the contents of the crucible a neutral or inert gas may be supplied through the pipe 19 and which will pass through the

perforated stand 18, up around the crucible 1, and out through the opening in the top of the casing surrounding the crucible mouth. This will prevent the air from reaching the contents of the crucible. Similarly a combustible gas may be supplied and burned as it escapes from the opening in the top of the casing. This will have a tendency to withdraw oxygen from the contents of the crucible and thus act as a reducing agent.

Each electrode is vertically adjustable in the jaws of the holder 32 so as to properly fit the crucible when moved up to it. Each electrode and its holder is horizontally adjustable in the clamp 35 independently of all other electrodes. This enables the operator to properly adjust the electrodes so that they will all engage the crucible when it is in the center of the casing and so that when the arcs are formed by retracting the electrodes, each electrode will be the same distance from the crucible as all the others. The carriages and gear connections cause the electrodes to all move simultaneously and through the same distance and at equal speeds so as to maintain equal arcs on all sides.

Changes in details of construction and substitutions of equivalents are of course contemplated and considered to be within the scope of the claims hereinafter set forth as will be understood by those familiar with the art of metal working.

What we claim is:

1. In an electric furnace, a tiltable casing, a crucible therein, a plurality of electrodes supporting said crucible when pouring and means for retracting said electrodes to form an arc.
2. In an electric furnace, a crucible, a plurality of electrodes having their faces shaped to fit the sides of the crucible and holders for said electrodes movable toward and from the crucible said electrodes being vertically removable from said holder.
3. In an electric furnace, a plurality of pairs of radially movable spring jaws having vertical openings and electrodes having wedge shaped posterior portions adapted to be inserted in the openings in said jaws and removable therefrom by vertical movement.
4. In an electric furnace, a crucible having a funnel shaped mouth and an outlet below the mouth electrodes arranged at the sides of the crucible and means for tilting said crucible to pour from said outlet.
5. In an electric furnace, a casing, a crucible therein, means for producing an arc, a spout leading from said crucible, a mold swinging from the casing and means for tilting the crucible and casing.
6. In an electric furnace, a tiltable casing, a crucible therein, a spout from the crucible leading beyond the edge of the casing, a small mouthed and relatively deep ingot pipe.

- mold pivotally carried by the casing on an axis immediately in front of the outlet end of said spout whereby the stream from the spout is discharged straight down in the 5 mold as the casing and crucible are tilted.
7. In an electric furnace, a tilttable casing, a crucible therein, a spout leading therefrom, a pair of hooks carried by the casing, affording an axis immediately in front of 10 the outlet from said spout and a mold having eye bolts adapted to be hung on said hooks for the purpose specified.
8. In an electric furnace, a casing, a plurality of horizontally movable jaws and a 15 vertically removable electrode carried by each jaw.
9. In an electric furnace, a casing, a crucible therein, a plurality of holders extending through said casing, an electrode carried 20 by each holder inside said casing and removable vertically therefrom and means outside said casing for moving said holders.
10. In an electric furnace, a crucible and a plurality of electrodes arranged around 25 the sides of the crucible and each extending substantially from the top to the bottom thereof.
11. In an electric furnace, a crucible, a plurality of electrodes, holders therefor, 30 means for radially adjusting the holders in-
- dependently and means for moving all the holders together.
12. In an electric furnace, a crucible, a plurality of holders, an electrode vertically insertible in each holder and means for 35 moving said holders.
13. In an electric furnace, a crucible, a plurality of holders, an electrode vertically insertible in each holder, and means for moving said holder radially. 40
14. In an electric furnace, a crucible, a plurality of independently adjustable holders, an electrode vertically insertible in each holder and means for moving said holders.
15. In an electric furnace, a casing comprising, a shell, a bottom therefor, a lining therein, a reinforcing hoop about the lower part of the shell, trunnion brackets secured to the bottom and shell and means for 45 tilting the casing. 50
